COMBINED BRUSH AND SHOE HOLDER

Charles W. Pennington, 16 Knob Hill Drive, Summit, N.J.

Filed Mar. 19, 1959, Ser. No. 55,057

Term of patent 14 years

(Cl. D33—3)

The dotted line indication of the brush and shoes are for illustrative purposes only.

I claim:

The ornamental design for a combined brush and shoe holder, as shown and described.
